UNITED STATES PATENT OFFICE.

JAMES P. MARTIN, OF LANCASTER, PENNSYLVANIA, ASSIGNOR TO LANCASTER IRON WORKS, INC., OF LANCASTER, PENNSYLVANIA, A CORPORATION OF PENNSYLVANIA.

BRICK-MACHINE MOLD.

Application filed February 28, 1924. Serial No. 695,682.

To all whom it may concern:

Be it known that I, JAMES P. MARTIN, a citizen of the United States, residing at Lancaster, in the county of Lancaster and 5 State of Pennsylvania, have invented a new and useful Improvement in Brick-Machine Molds, of which the following is a specification.

The present invention is an improvement 10 upon the brick machine mold described and claimed in Letters Patent of the United States No. 1,314,057 of August 26, 1919, to H. W. B. Graham, deceased, and its principal objects are first, to eliminate the carrying 15 back of clay or sand or other foreign substances into the sander; and second, to insure uniform and uninterrupted travel of the mold on the gravity wheel of the machine.

Other objects of the invention will appear 20 from the following description, and the invention, stated in general terms, may be said to comprise a brick machine mold having at each end a bumping block facially provided with a shoe extending uninterruptedly from one side of the mold to the other and consisting of a unitary metal plate.

The invention also comprises the improvements to be presently described and finally claimed.

In the following description reference will be made to the accompanying drawings forming part hereof and in which there is illustrated one embodiment of the invention selected from other embodiments and in the drawings

Figure 1 is a top or plan view of a brick machine mold embodying features of the invention.

Fig. 2 is a side elevational view of the same.

Fig. 3 is a sectional view taken on the line 3—3 of Figure 1.

Fig. 4 is a sectional view taken on the line 4—4 of Figure 1, and

Fig. 5 is an end view.

Referring to the drawings 1 are the side pieces, and 2 are the end pieces of the mold, and the mold is provided at its end with projecting members 3. 4 are metal plates co-extensive as unitary structures not only with the top surface of the members or

bumping blocks 3, but also with the top edges of the adjacent end pieces 2. These plates 4 constitute shoes that extend uninterruptedly from one side of the mold to the other.

One of the advantages of the described construction is that it prevents clay or sand or other foreign substance from being conveyed back into the mold sander by the molds, and this it does because of the continuity of the shoes 4, which present no cracks or cavities such as, if filled with clay or other foreign substance, would, when the mold got back in the mold sander and met the hot dry sand, permit it to dry out and fall off into the mold sander and dirty the sand. The described shoes or plates 4 extending from side to side of the mold at the ends thereof do not interfere with the action of the mold on the gravity wheels of the brick machine with which it is especially adapted for use and which is known in the trade as the Auto-Brik Machine. Expansion and contraction of the wood or lumber of the bumping blocks and molds, such as occur through soaking in water and then drying out, do not disturb or substantially disturb the surface of the shoes 4, thus no obstruction is presented to the gravity wheels and uniform and uninterrupted travel of the mold on the gravity wheels is insured. The brick machine and the parts or features of it to which reference has been made are too well understood to require illustration or description.

I claim:

1. A brick machine mold having side and end pieces and having at its ends projecting bumping members and provided at the ends with solid metal plates co-extensive as unitary structures not only with the top surfaces of the members but also with the top edge of the adjacent end piece.

2. A brick machine mold having at each end a bumping block facially provided with a shoe extending uninterruptedly from one side of the mold to the other and consisting of a unitary metal plate, substantially as described.

JAS. P. MARTIN.
